UNITED STATES PATENT OFFICE

FRANK A. LOVRICH, OF DAMSITE, MISSOURI

CURTAIN AND ADJUSTABLE SHADE SUPPORT

Application filed December 6, 1930. Serial No. 500,618.

This invention relates to a curtain and adjustable shade support and has for its primary object to provide, in a manner as hereinafter set forth, a device of this character embodying a novel construction and arrangement of parts whereby the shade and shade roller may be expeditiously adjusted vertically to any desired position relative to a window and maintained in adjusted position.

Other objects of the invention are to provide a curtain and adjustable shade support of the character described which will be simple in construction, strong, durable, attractive in appearance and which may be manufactured and installed at low cost.

All of the foregoing and still further objects and advantages of the invention may become apparent from a study of the following specification, taken in connection with the accompanying drawings wherein like characters of reference designate corresponding parts throughout the several views, and wherein:

Figure 1 is a view in front elevation of an embodiment of the invention.

Figure 2 is a view in side elevation of the invention.

Figure 3 is a detail view in top plan of one of the upper brackets.

Figure 4 is a horizontal cross sectional view taken substantially on the line 4—4 of Figure 1.

Figure 5 is a vertical sectional view through one of the lower brackets taken substantially on the line 5—5 of Figure 1.

Figure 6 is a vertical sectional view through one of the lower brackets taken substantially on the line 6—6 of Figure 1.

Figure 7 is a horizontal cross sectional view taken substantially on the line 7—7 of Figure 1.

Referring to the drawings in detail, it will be seen that the reference numeral 1 designates a pair of what will be hereinafter referred to as lower brackets which are provided with suitable openings for the passage of securing elements such as screws or the like for mounting said lower brackets on the lower portion of a window frame.

Each of the lower brackets 1 comprises a stationary or base portion 2 which is anchored to the window frame and which has its outer portion provided with a horizontal groove 3 for the reception of a tongue 4 formed integrally on one side of a movable section or portion 5. The tongue 4 is slideable longitudinally in the groove 3 toward and away from the window frame upon which the lower brackets are mounted. The stationary portion 2 of each of the brackets 1 is provided with a bore 6 which communicates with the groove 3 and with the socket 7 in the tongue 4 and the movable portion or section 5. Mounted in each of the lower brackets 1 is a coil spring 8 which is disposed in the bore 6 and the socket 7 and has its ends operatively connected with the stationary and movable sections 2 and 5, respectively, through the medium of the cross pins 9 and 10, respectively. The pin 9 is countersunk in the face of the stationary section 2 which is engaged with the window frame and the pin 10 intersects the inner portion of the socket 7. The portions of the stationary sections 2 of the lower brackets 1 which are above and below the groove 3 are provided with vertically aligned openings 11 and the tongue 4 is provided with a vertically extending opening 12 which is adapted to be brought into vertical alignment with the openings 11 when the movable section 5 is moved in a direction away from the stationary section 2. It may be well to here state that the coil springs 8 yieldingly pull the movable sections 5 toward the stationary sections 2 of the lower brackets 1. The opening 12 is normally out of vertical alignment with the openings 11 and the purpose of said openings 12 and 11 will be more fully hereinafter set forth.

Upper brackets designated generally by the reference numeral 13 are provided with apertured base portions 14 for securing said upper brackets in position on the upper portion of the window frame in vertical alignment with the lower brackets 1. Each upper brackets 13 includes an integral arm portion 15 provided with openings 16 for the passage of curtain supporting rods 17. Each of the upper brackets 13 is provided with a recess

18 which extends upwardly thereinto from its lower side and has rotatably mounted therein a grooved pulley 19.

Vertical guide rods 20 extend between the upper and lower brackets 13 and 1 and are supported thereby. Curtain supporting blocks 21 are slidably mounted on the guide rods 20 and have vertical openings 22 extending therethrough inwardly of the guide rods 20. The inner end of one of the blocks 21 is provided with a channel 23 extending downwardly thereinto from its upper side for the reception of one of the pintles on the shade roller 24 and the other of the blocks 21 has its inner end provided with a socket for the reception of the other pindle on the other end of the shade roller 24. It will thus be seen that the shade roller 24 is rotatably supported between the inner ends of the supporting blocks 21.

Suitable cables or ropes 25 are trained over the pulley wheels 19 and extend through the openings 22 in the blocks 21 and are secured to the blocks 21 for actuating said blocks in a vertical plane by set screws or the like 26. The end portions of the cables or ropes 25 are operable through the openings 11 and 12 in the lower bracket 1 and have secured to their ends suitable gripping handles or knobs 27.

As best seen in Figure 6 of the drawings, the cables or ropes 25 are normally frictionally clamped against movement by the tongues 4 of the movable sections 5, said movable sections 5 being actuated by the springs 8. The openings 11 and 12 are disposed on opposite sides of the springs 8. When it is desired to adjust the window shade vertically the movable sections 5 of the lower brackets 1 are moved outwardly against the tension of the coil springs 8 in a manner to release the lower portions of the cables or ropes 25 after which said cables or ropes may be actuated in either direction over the pulley wheels 19 to move the shade supporting blocks 21 either upwardly or downwardly on the guide rollers 20, as will be apparent. When the movable sections 5 of the lower brackets 1 are released the cables or ropes 25 are again frictionally and securely clamped against movement and the shade is thus secured in adjusted position. As seen in Figure 4 of the drawings, the guide rods 20 are of polygonal horizontal cross section and pass through correspondingly shaped openings in the supporting blocks 21 and in this manner rotation of the blocks 21 on the guide rods 20 is prevented.

It is believed that the many advantages of a device in accordance with this invention will be readily understood, and although the preferred embodiment of the invention is as illustrated and described, it is to be understood that changes in the details of construction may be had which will fall within the scope of the invention as claimed.

What is claimed is:—

1. A curtain and shade supporting structure comprising a pair of upper brackets and a pair of lower brackets attached to a window frame, a guide rod of polygonal cross section extending between each of the corresponding upper and lower brackets and supported thereon, a block mounted for vertical sliding movement on each of said guide rods each block having a polygonal opening therein for the passage of the respective guide rod for retaining the blocks against rotation, said blocks engageable with the respective ends of a shade roller in a manner to rotatably support said shade roller therebetween, each block being further provided with a vertical opening in its intermediate portion, the upper brackets each being provided with a recess, a pulley journaled for rotation in each recess, a flexible cable trained over each pulley and having its end portions depending therefrom, one of said end portions of each cable extending through the vertical opening in each of the blocks, a set screw securing each of the blocks to one of the cables, and means on each of the lower brackets for frictionally retaining the end portions of each of the cables against movement. 70 75 80 85 90 95

2. In a curtain and shade supporting structure a pair of upper brackets and a pair of lower brackets attached to a window frame, each of the lower brackets comprising a stationary base section for attachment to the window frame and a movable clamping section mounted on the stationary section, an integral tongue on each clamping section, each stationary section having a groove for slidably receiving the tongue, each tongue and the adjacent portions of said respective stationary sections having an opening, said openings adapted to be brought into alignment, a vertical guide rod extending between each of the corresponding upper and lower brackets, a block slidably mounted on each of the guide rods, said blocks being engageable with the respective ends of a shade roller for rotatably supporting said shade roller therebetween, a pulley rotatably mounted on each of the upper brackets, a cable trained over each of the pulleys and having its end portions depending therefrom, means for operatively connecting each of the cables to a respective one of the blocks for actuating said blocks, the end portions of each of the cables extending through the openings in the tongue and the stationary section, and resilient means operatively connected with the movable section of each of the lower brackets for actuating said movable section in a manner to frictionally clamp the end portions of each of the cables in the stationary section of the respective lower bracket. 100 105 110 115 120 125 130

3. A curtain and shade supporting structure comprising a pair of upper brackets and

a pair of lower brackets attached to a window frame, each of the lower brackets comprising a stationary base section for attachment to the window frame and a movable
5 clamping section mounted on the stationary section, an integral tongue on each of the clamping sections, each of the stationary sections being provided with a groove for slidably receiving a corresponding one of the
10 tongues, each of said tongues and the adjacent portions of each of the stationary sections being provided with corresponding pairs of openings each opening of the tongue adapted to be brought into alignment with
15 a corresponding opening in the stationary section, vertical guide rods extending between each of the corresponding upper and lower brackets, a block slidably mounted on each of the guide rods, said blocks being
20 engageable with the respective ends of a shade roller for rotatably supporting said shade roller therebetween, a pulley rotatably mounted on each of the upper brackets, a cable trained over each of the pulleys and
25 having its end portions depending therefrom, means for operatively connecting each of the cables to a respective one of the blocks for actuating said blocks, the end portions of each of the cables extending through cor-
30 responding openings in each of the tongues and each of the stationary sections of each of the lower brackets, resilient means operatively connected with the movable section of each of the lower brackets for actuating said
35 movable section in a manner to frictionally clamp the end portions of each of the cables in the stationary section of the respective lower bracket, said means each comprising a coil spring having one end anchored to the
40 respective stationary section and its other end anchored to the respective movable section.

In testimony whereof I affix my signature.
FRANK A. LOVRICH.
